CLAIM

The ornamental design for a packaging box, as shown and described.

DESCRIPTION

The file of this patent contains at least one drawing executed in color. Copies of this patent or patent application publication with color drawing(s) will be provided by the Office upon request and payment of the necessary fee.

FIG. 1 is a top perspective view of a packaging box in green in accordance with our design;

FIG. 2 is a front view of the packaging box in green in accordance with our design;

FIG. 3 is a back view of the packaging box in green in accordance with our design;

FIG. 4 is a left view of the packaging box in green in accordance with our design;

FIG. 5 is a right view of the packaging box in green in accordance with our design;

FIG. 6 is a top view of the packaging box in green in accordance with our design;

FIG. 7 is a bottom view of the packaging box in green in accordance with our design;

FIG. 8 is a top perspective view of a packaging box in pink in accordance with our design;

FIG. 9 is a front view of the packaging box in pink in accordance with our design;

FIG. 10 is a back view of the packaging box in pink in accordance with our design;

FIG. 11 is a left view of the packaging box in pink in accordance with our design;

(Continued)

FIG. 12 is a right view of the packaging box in pink in accordance with our design;
FIG. 13 is a top view of the packaging box in pink in accordance with our design;
FIG. 14 is a bottom view of the packaging box in pink in accordance with our design;
FIG. 15 is a top perspective view of a packaging box in yellow in accordance with our design;
FIG. 16 is a front view of the packaging box in yellow in accordance with our design;
FIG. 17 is a back view of the packaging box in yellow in accordance with our design;
FIG. 18 is a left view of the packaging box in yellow in accordance with our design;
FIG. 19 is a right view of the packaging box in yellow in accordance with our design;
FIG. 20 is a top view of the packaging box in yellow in accordance with our design;
FIG. 21 is a bottom view of the packaging box in yellow in accordance with our design;
FIG. 22 is a top perspective view of a packaging box in blue in accordance with our design;
FIG. 23 is a front view of the packaging box in blue in accordance with our design;
FIG. 24 is a back view of the packaging box in blue in accordance with our design;
FIG. 25 is a left view of the packaging box in blue in accordance with our design;
FIG. 26 is a right view of the packaging box in blue in accordance with our design;
FIG. 27 is a top view of the packaging box in blue in accordance with our design;
FIG. 28 is a bottom view of the packaging box in blue in accordance with our design;
FIG. 29 is a top perspective view of a packaging box in white in accordance with our design;
FIG. 30 is a front view of the packaging box in white in accordance with our design;
FIG. 31 is a back view of the packaging box in white in accordance with our design;
FIG. 32 is a left view of the packaging box in white in accordance with our design;
FIG. 33 is a right view of the packaging box in white in accordance with our design;
FIG. 34 is a top view of the packaging box in white in accordance with our design; and,

FIG. 35 is a bottom view of the packaging box in white in accordance with our design.

The broken lines shown in the drawings are for the purpose of illustrating parts of the article that form no part of the claimed design. The faded-out areas illustrate portions of the article that form no part of the claimed design.
